APPARATUS FOR SCORING ICE.

Application filed July 1, 1927. Serial No. 202,891.

This invention relates to apparatus of the kind that is used in ice plants for scoring large cakes or blocks of ice so as to facilitate dividing the ice cakes into smaller pieces, 5 each of a definite weight and size. The conventional ice scoring apparatus is expensive to build and to operate, as it comprises saws for forming scores or grooves in the cakes of ice, and electrically-operated devices for 10 driving the saws.

The main object of our invention is to overcome the necessity of using expensive machinery in the operation of scoring ice. To this end we have devised a novel apparatus 15 for scoring cakes of ice, that comprises one or more heated scoring devices, preferably a device of gradually increasing depth or height, and means for presenting cakes of ice to said devices and causing said cakes to 20 travel longitudinally of said devices, thereby causing grooves to be formed in said cakes, due to the melting of the ice. The scoring devices may vary in number and they can be constructed and arranged in various ways 25 without departing from the spirit of our invention.

Figure 1 of the drawings is a vertical longitudinal sectional view of an apparatus constructed in accordance with our invention.

Figure 2 is a top plan view of said apparatus.

Figure 3 is a side elevational view of said apparatus.

Figure 4 is a transverse sectional view, 30 taken on the line 4—4 of Figure 3; and

Figures 5 and 6 are enlarged cross-sectional views, illustrating two different ways of constructing the scoring devices of the apparatus.

In the machine herein shown, which represents the preferred form of our invention, two groups of scoring devices are arranged in opposed relation so as to form scores or grooves in two of the opposed faces of the 40 cakes of ice, for example, the top and bottom faces of said cakes, and the scoring devices constituting each of said groups are arranged in parallel relation. The cakes of ice α are moved longitudinally of said devices either by gravity or by a suitable feeding mechanism, and while traveling over said devices become scored or grooved, due to the ice melting where it contacts with the devices A. One convenient way of heating the scoring devices A is to circulate hot water through

tubes B with which the scoring devices are combined, but any other suitable heating medium may be used, such as steam, hot gases or electric current. As shown in Figure 5, each of the scoring devices C may consist of a metal blade set in a slot in a tube or other hollow structure B and permanently combined with same by a welding, brazing, soldering, or, in any other suitable way, the blade extending longitudinally of the tube 60 and projecting from the exterior of the same a distance equal to the depth of the scoring or slot it is desired to form in the ice. Due to the fact that the portion of the blade A that is arranged inside of the tube B is in direct 70 contact with the heating medium in said tube, the portion of the blade that contacts with the ice will be maintained at a sufficiently high temperature to cause the ice to melt rapidly, or, in other words, to insure the scoring device A sinking into the ice while the ice cake α is moving longitudinally of said scoring device. Instead of forming the scoring device from a blade separate and distinct from the tube or conduit that contains the 75 heating medium or through which the heating medium circulates, the scoring device may consist of an integral portion A' of a tubular member B' that contains the heating medium, as shown in Figure 6. The 80 scoring devices A preferably increase gradually in depth from the point where said cakes move out of engagement with said devices, as shown in Figures 1 and 3, so as to cause the scoring devices to sink gradually into the ice 85 or form the scores progressively. While we have stated that the ice cakes are preferably moved relatively to the scoring devices during the scoring operation, we wish it to be understood that our broad idea contemplates 90 moving the scoring devices relatively to the ice on which said scoring devices are acting.

In order to prevent the weight of the cakes of ice from being imposed on the heating tubes B that are combined with the group of 100 scoring devices A that act on the bottom face of said cakes, rails C are provided for the ice cakes to travel on during the scoring operation, said rails being arranged parallel to the scoring devices between the same, as shown in 105 Figure 2. Similar rails C are also preferably combined with the top group of scoring devices, as shown in Figure 4, so as to co-operate with the bottom rails to form a runway for the cakes of ice which corresponds 110

in depth to the thickness of said cakes. When hot water, hot gases, steam or a similar medium is used to heat the scoring devices A, it is preferable to attach the tubes B combined with each group of scoring devices to an intake header D and a discharge header D', as shown in Figures 1, 2 and 3.

In the machine herein illustrated the rails C and C' between which the cakes of ice travel during the scoring operation are arranged in an inclined position between a receiving platform E and a discharge platform F, as shown in Figure 1, so that gravity may be used to move the ice cakes longitudinally of the scoring devices. Accordingly, it is preferable to equip the machine with some kind of a means that will insure the cakes of ice being presented to the scoring devices in an orderly manner. The means that we have herein illustrated for this purpose consists of endless sprocket chains G surrounding sprocket wheels G' that are connected to shafts G², said chains being provided with arms or projections G³ that move into engagement with the front end of the ice cakes as said cakes leave the discharge platform, and thus effectively prevent said ice cakes from assuming a crooked position or from becoming disposed at an angle to the rails C down which said cakes are traveling to the scoring devices, said arms or projections G³ moving automatically out of engagement with the cakes after said cakes start to travel over the scoring devices.

The machine can be provided with any suitable kind of a frame, designated as an entirety by the reference character H, for supporting the various elements previously described, and if desired, side guides can be arranged between the receiving platform E and the point at which the ice cakes first contact with the scoring devices, so as to insure said cakes passing preferably from the receiving platform onto the runway down which said cakes travel during the scoring operation.

A machine of the kind above described can be built for a fraction of the cost of the conventional ice scoring apparatus now generally used in ice plants, it can be operated at a low cost, due to the fact that the scoring devices are operated by a heating medium of which there is always an ample supply available in an ice plant; it is of such simple design that it is not liable to get out of order when in use, and the scoring devices of the machine do not require constant attention like saws, to keep them in an operative condition.

Having thus described our invention,

what we claim as new and desire to secure by Letters Patent of the United States is:

1. An apparatus for scoring ice, comprising a heated scoring device of gradually increasing depth or height that is adapted to be engaged with the ice, and means for producing relatively longitudinal movement between the ice and said device. 60

2. An apparatus for scoring ice provided with a scoring device, consisting of a hollow structure that contains a heating medium, and an ice engaging blade projecting beyond the exterior of said hollow structure and combined with the same in such a way that a portion of said blade is located inside of said structure in direct contact with the heating medium in same, whereby heat will be effectively transmitted to the projecting portion of the blade that enters the ice during the scoring operation. 70

3. An apparatus for scoring cakes of ice, comprising a plurality of heated scoring devices arranged in parallel relation, and means for feeding cakes of ice longitudinally of said devices in contact with the same so as to cause said devices to form grooves in the cakes. 80

4. An ice scoring machine, comprising a runway over which cakes of ice are adapted to be moved, and groups of heated scoring devices combined with said runway so as to form parallel grooves in opposed faces of the ice cakes that travel over the runway. 85

5. An ice scoring machine, comprising opposed groups of parallel, heated scoring devices of gradually increasing depth or height, and means for presenting cakes of ice to said devices and causing said cakes to travel longitudinally of said devices, thereby causing grooves to be formed in said cakes due to the ice melting. 95

6. An ice scoring machine, comprising opposed rails between which cakes of ice are adapted to travel, scoring devices arranged parallel to said rails and adapted to act on opposed faces of the cakes, and means for heating said devices. 100

7. An ice scoring machine, comprising a downwardly-inclined runway through which cakes of ice are adapted to travel by gravity, groups of heated scoring devices arranged longitudinally of said runway at the upper and lower sides of same, and means for maintaining the cakes in a uniform position while they are traveling down said runway towards said scoring devices. 105
